UNITED STATES PATENT OFFICE.

LONGLEY LEWIS SAGENDORPH, OF PHILADELPHIA, PENNSYLVANIA, AS-SIGNOR OF ONE-HALF TO CHARLES N. HARDER, OF PHILMONT, NEW YORK.

DESIGN FOR A METALLIC CEILING-STRIP.

SPECIFICATION forming part of Design No. 19,699, dated March 11, 1890.

Application filed February 17, 1890. Serial No. 340,795. Term of patent 14 years.

To all whom it may concern:

Be it known that I, LONGLEY LEWIS SAGENDORPH, a citizen of the United States, residing at Philadelphia, in the county of Philadelphia, State of Pennsylvania, have invented and produced a new and original Design for Metallic Ceiling-Strips, of which the following is a specification, reference being had to the accompanying drawings, forming a part thereof.

Figure 1 is a bottom view of the strip as the same would appear looking toward the ceiling, and Fig. 2 is a cross-section through said metallic strip.

The leading feature of my design consists of the longitudinal V-shaped corrugations A A, centrally located in the metallic strip, the outer edges of said strip terminating in the

longitudinal circularly-formed corrugations B B, as shown. The central V-shaped corrugations are separated and connected by the central flat portion a, the V-shaped corrugations A A and the outer circular corrugations B B being separated and connected by the flat portions b b, as shown.

What I claim is—

The design for a metallic ceiling-strip herein shown and described, the same consisting of the V-shaped longitudinal corrugations A A, centrally located in said strip, and the circular corrugations B B along the outer edges of said strip, as set forth.

LONGLEY LEWIS SAGENDORPH.
